OIL WELL SERVICING MAST

John Hart Wilson, Wichita Falls, Tex.

Application May 24, 1941, Serial No. 395,102

10 Claims. (CL. 189—16)

This invention relates to improvements in portable masts useful in the servicing of oil well equipment, and is particularly concerned with that type of mast which is formed in telescoping sections, the entire structure being pivotally mounted on a motor vehicle, whereby the mast may be readily transported to the place of use, swung into upright position without removal from the vehicle, and raised to maximum height by extension of the sections thereof.

It is the general object of the invention to provide a mast of the character described which is so constructed as to facilitate to the utmost the various operations performed by the use of such masts, such as the withdrawal of well pipe, the vertical racking of sections of pipe during cleaning, repair, or replacement of the well equipment, and the subsequent assembly and lowering of the pipe sections into the well.

It is a further object of the invention to provide an oil well servicing mast of the telescoping type characterized by maximum rigidity and minimum weight, and affording adequate resistance to stresses imposed thereon during the operations of withdrawing and lowering the pipe.

It is a feature of the invention that the mast is provided with an elevated platform by means of which the withdrawn pipe sections may be manipulated and racked, the platform being so constructed and arranged as to facilitate collapse and withdrawal thereof into the mast when the latter is retracted for transportation.

A further object of the invention is the provision of novel means for locking the mast sections in extended relation in such manner that the mast will be substantially erect when loaded to further the correct application and distribution of stress therein.

Further objects and features of the invention will be apparent from the following description taken in connection with the accompanying drawings, in which

Figure 1 is a side elevation of a vehicle mounted mast to which the invention has been applied;

Figures 2 and 3 are partial front and side elevations respectively of the lower section of the mast shown in Figure 1;

Figure 4 is a horizontal sectional view taken substantially on the line 4—4 of Figure 2;

Figures 5 and 6 are partial front and side elevations respectively of the upper section of the mast shown in Figure 1;

Figures 7, 8, and 9 are horizontal sectional views taken substantially on the lines 7—7, 8—8, and 9—9 of Figure 6;

Figure 10 is a side elevation of a portion of the upper mast section illustrating the working and racking platform in extended position;

Figure 11 is a horizontal section of a portion of the mast shown in Figure 10 illustrating the platform in plan;

Figure 12 is an enlarged detailed view of the latch mechanism shown in Figure 10 for retaining the platform in collapsed and withdrawn position;

Figure 13 is an enlarged fragmentary sectional view taken on the line 13—13 of Figure 10;

Figure 14 is an enlarged view, partly in section, of a portion of the structure shown in Figure 10;

Figures 15 and 16 are front and side elevations respectively of the upper end of the upper section of the mast;

Figure 17 is a front elevation of the upper portion of the lower mast section showing the upper mast section in elevated or extended relation therewith;

Figure 18 is a side elevation of the structure shown in Figure 17;

Figure 19 is a detailed view of the cooperative locking elements on the upper and lower mast sections; and

Figures 20 and 21 are fragmentary views, partly in section, of details embodied in the structures shown in Figures 17 and 18.

30 In order to facilitate an understanding of the invention, reference will be made to the several embodiments thereof illustrated in the accompanying drawings and specific language will be employed. It will nevertheless be understood that various further modifications of the devices illustrated herein, such as would fall within the province of those skilled in the art to construct are contemplated as part of the present invention.

40 Figure 1 illustrates the general arrangement of the several elements of the apparatus to which the invention is directed, the mast being shown in full lines in erect and extended position, the dotted lines indicating the position assumed by the mast when collapsed and lowered for transportation.

45 It will be observed that the mast is formed in two sections, a lower section 22 and an upper section 23. The lower section 22 is pivotally mounted at the rear of a vehicle 24 for swinging movement from a generally horizontal to a generally upright position. Thus a suitable cradle including structural elements 25, 26, and 27 may be secured to the vehicle body so as to extend upwardly and rearwardly therefrom, the cradle

being provided with suitable means, not shown, in which the lower mast section is trunnioned approximately at the point 28 for swinging movement from the inoperative to the operative position.

It will be observed by reference to the broken lines in Figure 1, which illustrate the mast when collapsed and swung to horizontal position, that the pivotal axis 28 about which the mast is swung is disposed adjacent the upper rather than the lower face of the mast. By so locating this pivotal axis, the mast may extend further to the rear than would otherwise be possible, it being noted that the point of support must be so disposed as to afford adequate clearance between the lower end of the mast and the ground when the mast is raised. This greater rearward extension of the mast affords increased leverage in elevating the mast by the usual hoisting lines 29 and also provides improved distribution of the mast weight on the vehicle, a greater proportion of the weight being carried by the rear vehicle wheels.

The upper section 23 of the mast telescopes within the lower section 22, being elevated or extended by means of a cable 31 which is manipulated by a windlass 32 on the vehicle 24. A further windlass 34 on the vehicle is employed to manipulate the cable 35 which passes over the crown sheaves, indicated generally at 36, in the upper portion of the upper mast section 23, and over a suitable block 37 to raise and lower the hook 38 and elevator 39 carried thereby, the latter being adapted to engage and withdraw the well pipe as illustrated in Figure 1.

The general arrangement of the various elements to which reference has just been made is known; the instant invention relates primarily to improvements in the construction of these elements and in the association therewith of further elements hereinafter described. The mast is generally rectangular in horizontal section and in the further description of the invention, that face of the mast which is directed toward the hoisting gear, or toward the right as viewed in Figure 1, will be referred to as the forward face, and the hoisting and stacking operations may be described as conducted at the forward face. The opposite face, directed toward the forward end of the truck, will be referred to as the rearward face. The remaining faces will be referred to as the side faces of the mast.

Turning now to Figures 2 to 4 inclusive, in which the structural details of the lower mast section are more particularly illustrated, it will be noted that a framework of structural members is employed, these structural members being so associated that the forward, rearward and side faces are constituted by a series of truss sub-sections, horizontal sections of the mast being rectangular. The principal load bearing elements are constituted by four upright angle members, one being located at each corner of the structure, the corner angles at the forward face being indicated at 42 and those at the rearward face at 43. These corner angles extend substantially the entire length of the lower mast section and constitute laterally supporting and guiding means for the upper mast section. A typical horizontal section is shown in Figure 4, showing the transversely extending angle members 45 which are secured to the corner angles 42 and 43 at intervals in the length of the mast to form a series of complete rectangles. The forward and rearward faces of the mast are braced by

diagonally arranged angle members 46 forming a series of X-frame structures which are secured to the transversely extending members 45 adjacent the central portions of the latter and secured at their ends to the corner angles 42 and 43. Further brace members 48 are associated with the angle members 46 in each of the sub-sections of the lower mast section to resist weaving and otherwise to strengthen the structure.

5 The side faces of the lower mast section are also braced by angle members 47 which extend between and are secured at their opposite ends to the corner angles 42 and 43, the members 47 being secured to the members 43 adjacent the transverse members 45 defining each of the sub-sections of which the mast is composed.

10 The various structural members of which the mast is composed are preferably welded together, with the exception that the rear face of the lower mast section is bolted to the remainder of the lower section to facilitate assembling and dis-assembling of the upper and lower mast sections. Thus the rear face of the lower section may be prefabricated by the welding of the various structural elements, and angle brackets 51 are welded to the rear corner angles 43 at intervals in the length of the latter. Bolted to each of the angle brackets 51 is a second angle bracket 57, and the adjacent structural elements 45 and 47 are welded to the bracket 57. This arrangement permits the location of welding jigs within the lower section to support the various structural elements during the welding operation, the jigs being withdrawn by unbolting and removing the rear face 15 of the lower mast section on completion of the welding operation. The upper section, herein-after more particularly described, may then be prefabricated, introduced in the lower section, and the rear face of the lower section again bolted in position. The elements just described are shown in some detail in Figure 4.

20 The load transmitted downwardly through each of the corner angles 42 is carried by pedestals 49, the latter being braced to the rearward corner angles 43 by a series of diagonally extending members 50. A pulley 52, carried principally by members 53 and 54, is provided for the cables 25 29 which serve to swing the mast from inoperative to operative positions about its horizontal axis of support on the vehicle.

25 The upper end of the lower mast section is shown in Figures 17 and 18 in association with the lower end of the upper mast section. Pulleys 55 and 56, suitably mounted at the upper end of the lower section, are utilized for raising the upper section within the lower section in a manner herein-after more particularly described, and means are provided for retaining the upper section in raised position, as herein-after explained.

30 Turning now to Figures 5 to 9 inclusive, which illustrate the upper mast section, it will be noted that, as in the case of the lower mast section, horizontal sections are generally rectangular in outline with the important exception that over a substantial portion of the length thereof the forward face is in effect recessed, the side faces extending forwardly beyond the rectangular outline so as to afford clearance for the hoisting gear and to provide for the reception of the platform in the upper mast section when the platform is folded. As in the case of the lower mast section, the vertical load is carried primarily on corner angle members, the forward corner angles being indicated at 58 and the rearward corner angles 35 at 59. The forward and rearward corner angles

at opposite sides of the mast section are connected by angle members 60, and transverse angle members 61 connect the rearward corner angles 59. Extending between and secured to the members 60, are angle members 62; a V-shaped brace constituted by angle members 63 extends between the central portion of each member 61 and the forward corner angles 58, being secured also to the members 62. Thus the members 60 to 63 inclusive define generally horizontal planes at intervals in the length of the upper mast section, typical horizontal sections being represented in Figures 7, 8, and 9, the upper mast section being thereby divided into sub-sections or short lengths.

The forward, rearward, and side faces of each sub-section are reinforced by a truss structure similar to that employed in the lower mast section. Thus the forward and rearward faces are reinforced by angle members 65 which extend between the corner angles 59 and between the ends of members 62 defining adjacent sub-sections, the members 65 constituting in effect X-braces which are secured at their central portions to the members 61 and 62. The side faces of the upper section are reinforced by angle members 68 which are secured at their ends to the forward and rearward corner angles 59 and 58 respectively.

The lowermost sub-section of the upper mast section need not be provided with the recessed forward face hereinbefore referred to, and the lower ends of the corner angles 58 and 59 are united by a rectangular structure comprising members 70 of rectangular or box-section. In the three lower sub-sections of the upper mast section the corner angles are uniformly spaced, the dimensions being such that these corner angles may be received with a slight clearance within the corner angles 42 and 43 of the lower mast section for sliding and telescoping movement therein, suitable wear pads 71 being preferably secured to the outer faces of the corner angles 58 and 59. Beginning with the fourth sub-section of the upper mast section, the rearward corner angles 59 are deflected toward the forward corner angles 58 so that the upper portion of the upper mast section decreases in transverse sectional area in an upward direction, corner angles 58 and 59 meeting at the extreme upper end of the mast. The uppermost section of the mast is reinforced by a suitable rearwardly extending truss structure, as shown in Figures 15 and 16, and the crown sheaves 36 are mounted on a transversely extending channel member 13 spanning the corner angles at their point of juncture at each side of the mast, so that the compression load applied during lifting operations by the crown sheaves is transmitted directly downward through the forward corner angles 58 to the box member 70 at the lower end thereof. It will be observed that the upper mast section is enlarged at its upper end by the truss structure shown in Figures 15 and 16. The dimensions of this structure are preferably such that while the mast sections may be completely telescoped, they will fit together with only slight clearance when in telescoped relation, the rearwardly extending truss structure of the upper section supporting the latter when the mast is collapsed for transportation.

While it is preferred, in the fabrication of the mast sections, that the various structural members shall be welded at their points of connection, so that each of the two mast sections shall constitute in effect an integral rigid framework, riveting or other means of securing the

structural elements together may nevertheless be resorted to under some circumstances. Structural members of a different type from those specifically described may be employed within the scope of the invention, the foregoing detailed description being merely illustrative of one form of structure characterized by extreme rigidity and light weight.

Turning again to Figures 17 to 19 inclusive, it will be observed that the cable 31, by means of which the upper section is elevated, passes over the pulleys 55 and 56 secured to the upper end of the lower section, beneath pulleys 75 and 76 secured to the lower end of the upper section adjacent the rearward face thereof, and is returned upwardly and fastened to the upper end of the lower section in any convenient manner.

Secured beneath the box member 70 to which the compression load of the upper section is transmitted are shoes 80, these shoes being disposed at opposite sides adjacent the forward face of the mast. Journalled in suitable bearings at each side of the lower mast section are rock shafts 81, each of these rock shafts carrying an arm 82 which is arranged to engage beneath the adjacent shoe 80 to afford support for the upper mast section in its elevated position. Arms 83 on the rock shafts 81 are connected by a link 84, adjustable as to length, and an arm 85 on one of the rock shafts 81 is connected by a similarly adjustable link 86 to a lever 87 pivoted on the lower mast section, releasable pawl and ratchet mechanism being associated with the lever to retain the same against unintentional displacement. When the lever 87 is rocked in a downward direction, each of the arms 82 is brought beneath the associated shoe 80 and occupies the position illustrated in Figure 19. The engaging surfaces of the arms 82 and shoes 80 are preferably cylindrical segments of which the axis, indicated at 88, is slightly offset from the axis of the associated rock shaft 81, so that when the arms are partially withdrawn from the shoes, as shown in dotted lines in Figure 19, ample clearance is afforded between the cooperating surfaces. Thus the arms 82 may readily be moved into position beneath the shoes 80, but on completion of this movement, which is limited by engagement of a projection 89 on the upper end of each arm 82 with the associated shoe 80, the cooperating surfaces of the arms 82 and shoes 80 will be tightly engaged.

Referring now to Figure 20, illustrating on a larger scale certain of the structure shown in Figure 18, it will be noted that bracket means indicated generally at 90, mounted on and adjacent the upper extremity of each corner angle 42 of the lower mast section, affords a support for a threaded element 91. Adjustably mounted on the threaded element 91 is a shoe 92 having a downwardly directed bevelled surface 93 coacting with a correspondingly bevelled surface on a shoe 94 secured to the adjacent corner angle of the upper mast section. It will be appreciated that as the upper mast section approaches the upper limit of its movement, these coacting bevelled surfaces will engage and exert a rearward thrust on the upper mast section. By slightly adjustment of the position of the shoe 92 longitudinally of the mast, this forward wedging action may be completed so as to force the corner angles 59 of the upper mast section against the upper extremity of the rear-

ward corner angles 43 of the lower mast section when the upper mast section occupies such a position that the coacting surfaces of the arms 82 and shoes 80 are in full engagement as shown in Figure 19, and the arms thus serve to maintain this rearward wedging action on the upper mast section.

In Figure 17 is shown a spindle 140 suitably mounted on the lower mast section and carrying a bevel gear 141. A coacting bevel gear 142 carries a sprocket over which is passed a chain 145. The chain 145 engages sprockets 146, each sprocket being mounted on a spindle 147 having threaded engagement in a boss 148, as shown more particularly in Figure 21. The bosses 148 are mounted respectively on the corner angles 43 of the lower mast section, and the spindles 147 extend through these corner angles and engage at their free ends 150 with the adjacent faces of the corner angles 59 of the upper section. Thus when the spindle 146 is rotated manually, the sprocket chain 145 rotates the spindles 147 in such a direction that the latter engage and thrust forwardly the lower ends of the corner angles 59 of the upper mast section.

It will thus be seen that I have provided means at the upper end of the lower mast section for wedging the adjacent portion of the upper mast section rearwardly, and means at the lower end of the upper mast section for forcing the latter forwardly, whereby the upper mast section may be tilted rearwardly when free from load. The extent of tilting is slight, but is preferably sufficient to ensure that when loaded to approximately rated capacity, the forward corner angles of the mast will be substantially straight, and the load will be transmitted directly downward from the crown sheaves 36 through the substantially aligned and straight corner angles 58 and 42 to the pedestals 49 and thence to jacks or other suitable objects placed beneath the pedestals. In other words, by means of the mechanism just described, it is possible to tilt the upper section on the lower section so as to bow the mast forwardly. It will be appreciated that when the load is applied to the mast, the structural members at the forward side of the mast will be subjected to the greatest compression, with the result that the central portion of the mast will be deflected rearwardly. By initially tilting rearwardly or bowing the mast forwardly, as hereinbefore set forth, the effect of the load on the mast may be substantially counteracted, and the load carrying capacity is accordingly substantially increased.

In Figures 10 to 14 inclusive, is shown the collapsible platform which facilitates manipulating and racking of the withdrawn pipe sections. When viewed in plan, as shown in Figure 11, the platform is generally U-shaped, having the legs of the U directed toward the mast, so as to provide an opening through which the lifting gear may be raised and lowered and through which the pipes may extend when elevated, the pipes being retained when stacked by the surrounding platform. The platform is supported principally by a U-shaped box frame indicated at 95, the forward ends of the frame being pivoted at 96 to the mast. Supported on the frame 95 are the lateral rectangular aprons 97, a rearward rectangular apron 98, and two generally triangular aprons 99, these aprons forming, when extended laterally, a catwalk about the generally rectangular opening defined by the frame 95. As shown in

Figures 13 and 14, each apron may comprise a supporting framework of angle sections 101 carrying a sheet metal member 102 forming the floor of the apron. Each rectangular apron is 5 separately pivoted to the supporting box frame so as to permit the same to swing upwardly and inwardly, so that when folded these aprons occupy a position within the confines of the box frame. Inwardly directed abutments 103 are provided on the latter to support the apron 98 in its 10 inwardly folded position, and the aprons 97 thereon. The triangular aprons 99 may be hingedly supported on adjacent structures but are preferably detachably mounted for removal prior to 15 folding of the rectangular aprons.

The platform is surrounded by a railing, serving the function of protecting the operator. Thus a stanchion 105 is pivotally connected to each outer corner of each of the rectangular aprons and also to the central portion of each of the aprons 97, each stanchion being formed in two sections which are pivoted together as indicated at 106 and retained in aligned position by a sleeve 107 which is arranged to slide over the adjacent 20 ends of the stanchion sections. The lower sections of the stanchions associated with each of the aprons are reinforced by a tubular bar 109 extending therebetween and secured thereto, and a similar tubular bar unites the upper sections of 25 these stanchions. The stanchions 105 adjacent the mast are provided with sockets 111, and corresponding sockets 112 are provided on the mast, so that these stanchions may be locked in upright 30 position with relation to the mast by inserting the angularly disposed ends of a rod 114 in the respective sockets. Similar sockets 116 are provided on the stanchions 105 at the rear outer corners of the aprons 97 and 98, so that these stanchions 35 may similarly be locked together by means of bars 117. Cables 118 are secured to the box frame 95 at the juncture of the legs thereof with the base, indicated at 119, these cables passing over pulleys 120 supported on the upper mast section adjacent 40 the upper end of the latter, and thence extending downwardly to the vehicle or some other point 45 for convenient manipulation to raise and lower the platform.

It will be apparent from the foregoing description 50 that the railing around the platform may be collapsed and swung inwardly on the associated aprons and that the latter may then be swung upwardly and inwardly into a position within the confines of the supporting frame 95, as hereinbefore suggested. When so collapsed, each platform and its associated railing will appear substantially as shown in dotted lines in Figure 13. The removal of the rods 114 permits the lowering of the collapsed platform which 55 swings about the point of pivotal connection 96 with the mast to a position within the confines of the mast and adjacent the recessed rearward face thereof, the dotted line position of the withdrawn platform being shown more particularly 60 in Figure 12. This figure also discloses a method of retaining the platform in collapsed and withdrawn position, consisting essentially of a counter-balanced latch 125 pivoted on an arm 126 which is in turn pivoted to a transverse angle member 127 forming part of the upper mast section structure. To the upper end of the arm 126 is pivoted a member 128 which extends through an apertured element 129 mounted on an angle member 65 68 of the upper mast section. The member 128 is threaded at its outer end to receive 70

a nut 130 provided with a handle 131 by which the same can conveniently be turned. A coil spring 132 is connected between the latch 125 and the rearward end of the member 128 to urge the latch upwardly. A cooperating latch 135 is secured to the lower side of the box frame 35 of the platform, the noses of the cooperating latch members being so shaped that engagement as shown in Figure 12 automatically occurs when the platform is swung downwardly against the mast. If the nut 130 be turned downward after latching engagement occurs, the arm 126 will be displaced to the left to increase the friction between the latching surfaces so as to prevent unintentional release of the platform. The nut 130 further affords a means whereby the proper position of the toe of the latch 125 may be established so as to ensure that the platform will be locked in a position clear of the lower mast section when the mast sections are telescoped.

In the use of the apparatus, an operator standing on the extended platform may manipulate the hoisting gear so as to stack the pipe in sections consisting of two standard pipe lengths within the confines of the platform as shown in Figure 1. The recessing of the forward face of the upper section of the mast affords adequate clearance for the hoisting gear without appreciable reduction of strength, beside affording space for the stowing of the collapsible platform. The corner angles of the two sections, and particularly the forward corner angles, afford adequate and direct support for the load and also serve as guide members by means of which the two mast sections are directed during the telescoping movement thereof.

Having thus described the invention, what is claimed as new and desired to be secured by Letters Patent is:

1. A portable mast adapted to be pivotally mounted on a mobile base for use in connection with oil drilling operations, comprising a lower structure of rectangular section and substantially uniform in transverse dimensions throughout its length, an upper structure mounted in telescoping relation with said lower structure, said upper structure being of generally rectangular section, the forward face of said upper structure being spaced rearwardly of the forward edges of the adjacent side faces to provide a recessed front, and a collapsible working platform connected to said upper structure in such manner as to be movable to a generally horizontal position when said mast is in raised position and to be folded into the recessed front of said upper structure when not in use.

2. In combination with the construction defined in claim 1, latch means associated with said upper structure for engaging and retaining said platform in folded position, and means for locking said latch means against accidental disengagement.

3. A portable mast adapted to be pivotally mounted on a mobile base for use in connection with oil drilling operations, comprising a lower structure of rectangular section and substantially uniform in transverse dimensions throughout its length, an upper structure mounted in telescoping relation with said lower structure, said upper structure being of generally rectangular section, the forward face of said upper structure being spaced rearwardly of the forward edges of the adjacent side faces to provide a recessed front, means mounted adjacent the upper end of said lower structure for supporting said

upper structure in raised position, and means for tilting said upper structure slightly rearwardly relative to said lower structure whereby said mast is bowed slightly forwardly when not under load, and is substantially straight when under normal load.

4. A portable mast for use in connection with oil drilling operations comprising a lower structure, an upper structure mounted in telescoping relation with said lower structure, means mounted adjacent the upper end of said lower structure for supporting said upper structure in raised position, and means for tilting said upper structure slightly rearwardly relative to said lower structure whereby said mast is bowed slightly forwardly when not under load, and is substantially straight when under normal load.

5. A portable mast for use in connection with oil drilling operations comprising a lower structure, an upper structure mounted in telescoping relation with said lower structure, means mounted adjacent the upper end of said lower structure for supporting said upper structure in raised position, and means for tilting said upper structure slightly rearwardly relative to said lower structure whereby said mast is bowed slightly forwardly when not under load, and is substantially straight when under normal load, said last named means including cooperating wedges carried by said lower and upper structures and engaged as said upper structure is raised.

6. A portable mast adapted to be pivotally mounted on a mobile base for use in connection with drilling operations, said mast comprising upper and lower telescoping sections, and means acting between said sections to lock the upper section in extended position, said means including at least one arm pivoted on said lower section and a shoe rigid with said upper section, said arm and shoe being formed to provide cooperating, similarly shaped segmental cylindrical surfaces of which the axis is disposed laterally of the pivotal axis of said arm, whereby the clearance between said surfaces gradually decreases as the arm is moved in shoe engaging direction.

7. A portable mast adapted to be pivotally mounted on a mobile base for use in connection with drilling operations, said mast comprising upper and lower telescoping sections, means acting between said sections to lock the upper section in extended position, and means including wedge means on said mast sections affording cooperating surfaces exerting a rearward thrust on said upper mast section when the latter is extended to tilt the same with respect to the lower mast section.

8. A portable mast adapted to be pivotally mounted on a mobile base for use in connection with drilling operations, said mast comprising upper and lower telescoping sections, means adjacent the upper end of the upper section for supporting hoisting gear at the forward side of said mast, means acting between said sections to lock the upper section in extended position with the two sections in telescoped relation over a substantial portion of the length thereof, means acting between said sections adjacent the upper end of the lower section for exerting a rearward thrust on the upper section, and means acting between said sections adjacent the lower end of the upper section for exerting a forward thrust on said upper section, whereby said upper section is tilted rearwardly when unloaded to compensate for forward bending of the mast on

application of a normal load to the hoisting gear.

9. A portable mast adapted to be pivotally mounted on a mobile base for use in connection with drilling operations, said mast comprising upper and lower telescoping sections, means adjacent the upper end of the upper section for supporting hoisting gear at the forward side of said mast, means acting between said sections to lock the upper section in extended position with the two sections in telescoped relation over a substantial portion of the length thereof, and means applying thrust between said sections in opposite directions at vertically spaced points for tilting the upper section rearwardly when

unloaded to compensate for forward bending of the mast on application of a normal load to the hoisting gear.

10. A collapsible platform for use with an oil well maintenance mast, comprising a supporting frame defining a generally rectangular opening, and aprons hinged to said frame for swinging movement from an operative position in which they extend laterally of three sides of said opening to an inoperative or collapsed position in which they lie within said opening and are encompassed by said frame.

JOHN HART WILSON.
